UNITED STATES PATENT OFFICE.

WILLIAM ILE, OF JACKSON, MICHIGAN, ASSIGNOR TO REYNOLDS SPRING COMPANY, OF JACKSON, MICHIGAN, A CORPORATION OF DELAWARE.

ELECTRIC SWITCH.

Application filed May 26, 1925. Serial No. 33,047.

The invention relates to a noiseless electric switch.

The object of the present invention is to provide a noiseless electric switch of simple, 5 strong and durable construction adapted to be cheaply manufactured and capable of effecting a quick make and break.

With these and other objects in view, the invention consists in the construction and 10 novel combination and arrangement of parts hereinafter fully described, illustrated in the accompanying drawings and pointed out in the claim hereto appended, it being understood that various changes in the form, 15 proportion and minor details of construction, within the scope of the claim, may be resorted to without departing from the spirit or sacrificing any of the advantages of the invention.

In the drawings:

Figure 1 is a longitudinal sectional view of a noiseless switch constructed in accordance with this invention.

Fig. 2 is a reverse plan view of the upper 25 section of the insulating base or body.

Fig. 3 is a plan view of the switch mechanism, the upper section of the insulator of base or body being removed.

Fig. 4 is a reverse plan view of the lower 30 section of the insulating base or body, the contact shell of the insulating washer being removed.

Fig. 5 is a detail view of the stationary switch contact.

Fig. 6 is a detail view of the insulating disk.

Fig. 7 is a plan view of the shell contact.

Fig. 8 is a central transverse sectional view of the noiseless switch.

Fig. 9 is a similar view taken substantially on the line 9—9 of Fig. 3.

In the accompanying drawing in which is illustrated the preferred embodiment of the invention the noiseless switch is shown applied to a lamp socket, the outer shell or casing and the usual lining being omitted for convenience of illustration. The insulating base is composed of upper and lower sections 1 and 2 provided with registering 45 semi-cylindrical recesses forming aligned cylindrical openings 3 and 4 and a reduced connecting cylindrical opening 5 for the reception of a threaded sleeve 6 and a key 7 having a stem or shaft 8 upon which the 50 sleeve is mounted. The sleeve which is con-

structed of brass or other conducting material is provided with a spiral groove 9 which is engaged by a stud 10 molded in the upper section of the insulating base and adapted to limit the longitudinal movement of the sleeve which is caused to move longitudinally of the opening 3 by a rotary movement of the key. The insulating base is designed to be constructed of bakelite or other suitable material.

The stem or shaft 8 is journalled in the reduced connecting portion 5 of the continuous bearing formed by the aligned openings 3 and 4 and the said reduced connecting portion 8 and the stem or shaft is equipped at its outer end with the said key 7 which is molded of bakelite or other suitable material and which consists of a cylindrical portion fitting the outer opening or portion 4 of the continuous bearing and provided at its outer end with a head 11 having a checkered or otherwise roughened periphery to enable it to be readily grasped for rotating the movable member formed by the stem or shaft the sleeve and the key to carry such movable member into and out of engagement with a stationary switch contact 12. The stationary switch contact 12 consists of a strip of metal bent to form an attaching plate or portion 13 and a contact portion which is bent transversely as clearly shown in Fig. 5 and which has its outer portion extending into the path of the movable member of the switch as clearly shown in Fig. 2 of the drawing. The terminal portion of the stationary switch contact is arranged substantially at right angles to the attaching portion 13 which is secured to the upper section 1 of the insulating base in an opening 14 formed by corresponding recesses in the lower face of the upper section 1 and the upper face of the lower section 2 of the insulating base. The stationary switch contact is secured to the upper section 1 of the insulating base by a bolt or screw 15 extending through an opening 16 in the upper section 1 and having a head at its upper end and threaded at its lower end to engage a threaded opening in an approximately L-shaped terminal 17 arranged in the opening 14 and carrying a binding screw 18 for the attachment of an end of a circuit wire. The upper end of the bolt opening 16 is counterbored or enlarged to arrange the head of the bolt below the upper

surface of the section 1 of the insulating base. The sleeve 6 which is provided with a spiral groove 9 is in constant electrical connection with a center contact 19 consisting of a strip of metal bent into approximately sigmoidal form and consisting of an upper contact portion 20, a lower contact portion 21 and an intermediate attaching portion 22. The lower section 2 of the insulating base is provided in its lower face with a recess 23 for the reception of the center contact and the attaching portion 22 thereof is riveted or otherwise secured at 24 to a transverse supporting plate 25 bridging the recess 23 at the inner portion thereof and secured by spaced vertical screws 26 to the insulating base. The screws 26 which also serve to secure the upper and lower section 1 and 2 of the insulating base together pass through registering vertical openings 27 thereof and have lower threaded ends 28 which engage threaded perforations in the end portions of the supporting plate 25. The upper ends of the bolt openings 27 of the upper section are enlarged to receive the heads of the bolts or screws 26 and the recess 23 which extends from one side of the lower section of the insulating base to within a short distance of the opposite side is provided adjacent to its inner end with lateral extensions or branches 29 which receive the end portions of the supporting plate 25 as clearly illustrated in Fig. 9 of the drawing. The upper contact portion of the center contact is angularly bent at its free end 30 into an approximately L-shape, the L-shaped end 30 extending through an opening 31 which connects the recess 23 with the bearing opening of the insulating base. The resiliency of the metal of the center contact maintains the L-shaped end portion 30 in firm contact with the contact sleeve of the stem or shaft 8. The lower contact portion of the center contact is connected with the intermediate attaching portion by a relatively large U-shaped bend 31' which extends the lower contact portion below and into a screw shell contact 32 secured to the lower face of the lower section 2 of the insulating base by screws 33 and 34 which pierce the flange 35 of the shell contact and also an insulating disk 36 as clearly shown in Fig. 8 of the drawing. The screw or bolt 33 extends upwardly from the lower face of the insulating base to an opening 37 formed by registering recesses in the lower face of the upper section 1 and in the upper face of the lower section 2 and located at a diametrically opposite point from the opening 14. The upper end of the screw 33 engages a threaded perforation in an L-shaped terminal 38 provided with a binding screw 39 for the attachment of the end of a circuit wire. The L-shaped terminals 17 and 38 have a corner or portion bent outwardly to cooperate with

the head of the screw confining the terminal of a circuit wire in the usual manner. The other screw 34 is provided at its upper end with a nut 40 which is arranged in a recess 41 in the lower section 2 of the insulating base at the bottom of the opening 14 to space the bolt from the terminals 17, sufficient air space being provided to insulate the parts.

The lower section 2 of the insulating base is provided at opposite sides of the recess 23 with depending flanges 42 located at opposite sides of the bend 31 of the center contact and forming abutments for the insulating disk 36 and the flange 35 of the shell contact. The flange 35 of the shell contact is provided with an opening 43 of sufficient size to clear the center contact and also to provide a passage for the supporting plate of the center contact in assembling the parts. The insulating disk is provided with an opening 44 and the side edges of the openings 43 and 44 fit against the outer side faces of the depending flanges 42 which form abutments and interlock the disk and the contact shell against relative rotary movement and relieve the fastening devices of strain in screwing a lamp into and out of the shell contact. By this construction the parts are firmly maintained in proper position and loosens and accidental short circuiting are effectually prevented. It will be clear from reference to Fig. 1 of the drawing that the movable member of the switch has but little distance to travel to engage and disengage the stationary contact of the switch and that the switch is perfectly noiseless in its operation. Also it will be clear that ample air space is provided at the contacted parts which not only reduces the amount of the bakelite but also insures proper insulation of the parts.

What is claimed is:

A noiseless switch including an insulating base composed of upper and lower sections provided in their opposing faces with registering recesses, a rotary switch member mounted between the upper and lower sections and having a spirally grooved contact portion, a stud embedded in one of the sections and engaging the spirally grooved contact portion of the switch member and causing a longitudinal movement of the same when the switch member is rotated, a stationary switch contact mounted in one of the said recesses and having a contact portion extending into the path of the movable switch member and arranged to be engaged by the inner end thereof, and a center contact secured to the insulating base and having a portion bearing against the spirally grooved contact portion of the rotary switch member.

In testimony whereof I have hereunto set my hand.

WILLIAM ILE.
